Des. 242,434
Patented Nov. 23, 1976

242,434

REVOLVING-INDICATOR WORLD TIME CLOCK

Charcia Fern Knowles, 329 Wildbriar Drive,
Garland, Tex. 75041

Filed Apr. 29, 1975, Ser. No. 572,657

Term of patent 14 years

Int. Cl. D10—01

U.S. Cl. D10—10

FIG. 1

FIG. 2

FIG. 3

FIG. 4

FIG. 5

FIG. 1 is a right rear perspective view of a revolving-indicator world time clock, showing my new design.

FIG. 2 is a left front side elevational view thereof.

FIG. 3 is a top plan view thereof.

FIG. 4 is a right rear side elevational view thereof.

FIG. 5 is an exploded right front elevational view thereof.

I claim:

The ornamental design for a revolving-indicator world time clock, as shown.
